UNITED STATES PATENT OFFICE

93,289

DESIGN FOR A BULLETIN BOARD OR SIMILAR ARTICLE

Max Rosner, Chicago, Ill.

Application April 23, 1934, Serial No. 51,483

Term of patent 14 years

To all whom it may concern:

Be it known that I, MAX ROSNER, a citizen of these United States, residing at 1522 N. Kedzie Av., in the city of Chicago, county of Cook, and State of Illinois, have invented a new, original, and ornamental Design for a Bulletin Board or Similar Article, of which the following is a specification, reference being had to the accompanying drawing forming part thereof.

I claim:

The ornamental design for a bulletin board or similar article as shown.

MAX ROSNER.
